UNITED STATES PATENT OFFICE.

JOSEPH LEON GOBEILLE, OF CLEVELAND, OHIO, ASSIGNOR TO ISAAC A. SHEPPARD, FRANKLIN L. SHEPPARD, AND HOWARD R. SHEPPARD, OF PHILADELPHIA, PENNSYLVANIA.

DESIGN FOR A COOK-STOVE.

SPECIFICATION forming part of Design No. 23,826, dated November 27, 1894.

Application filed October 3, 1894. Serial No. 524,837. Term of patent 14 years.

To all whom it may concern:

Be it known that I, JOSEPH LEON GOBEILLE, a citizen of the United States, and a resident of Cleveland, Ohio, have invented a certain 5 new and original Design for a Cook-Stove, of which the following is a specification.

My design for a cook stove is fully shown in the accompanying drawing, which represents a perspective view of the stove.

10 The legs 1 have, on their flared or widened upper portions, ornamentation consisting of a pair of ribbon scrolls 2 united at the center, both of said ribbon scrolls being precisely alike. Extending from one leg to the other 15 upon the bottom of the stove is an apron 3 comprising representations of opposite fluted or folded webs 4, a central ribbon 5 with in-turned scroll-like ends, and scrolls 6 extending from the ends of said ribbon to the webs 4.

20 The front fire door 7 has at the top a tablet 8 with ornamental border, and at the bottom a series of fluted or corrugated vertical ribs 9, and between said ribs and the tablet is a series of scrolls 10.

25 The side fire door 11 has ornamentations consisting of a ribbon scroll 12 extending along the top and bottom of the door and has a ribbed or corrugated hinge block 13.

30 The oven door has a central ornament consisting of a medallion 14 with female head and projecting star points, this medallion being mounted upon a background 15 having radiating arms extending from the medallion to the border of the ornament. The oven door 35 has also at the upper and lower rear corners ribbon scrolls 16 and 17 and another ribbon scroll 18 at the front end.

30 The end plate 19 of the water reservoir at the rear of the oven has a concave lower edge and a ribbon scroll 20 extending throughout the lower portion and up the rear edge of the plate. The back plate 21 has at each edge a ribbon scroll 22 projecting outwardly at top and bottom and extending from the top plate 45 of the stove to the elevated warming oven, the projecting lower portions of said scroll supporting the stands 23. On the center of

the back plate is the smoke flue, the front of which is ornamented by a lower tablet 24, an upper plate with a series of vertical openings 50 25, and a ribbon scroll 26 extending between said plate and the lower tablet and crossing a central band 27.

The warming oven 28 has end plate ornamentation consisting of ribbon scrolls 29 interlooped at the center of the plate and extending upward or downward toward each corner and the front doors 30 of the warming oven have ornamentation consisting of like interlooped ribbon scrolls 31, the central 60 portions of which, however, are covered by a plate 32. The warming oven has a top border consisting of central and corner ornaments 33 of a shell-like character, and intervening scrolls 34. 65

Around the lower edge of the warming oven extends a border 35 consisting of a row of arch-like ornaments, similar borders 35 extending around the stands 23, around the top plate of the stove, around the cover plate of the ash 70 pit, around the oven extension plate 36 and around the water heater plate.

I claim—

1. The design for a cook stove, substantially as described and shown. 75

2. In a design for a cook stove, the design for the leg, substantially as described and shown.

3. In a design for a cook stove, the design for the apron around the bottom of the stove, substantially as described and shown. 80

4. In a design for a cook stove, the design for the front fire door, substantially as described and shown.

5. In a design for a cook stove, the design for the side fire door, substantially as described and shown. 85

6. In a design for a cook stove, the design for the oven door, substantially as described and shown. 90

7. In a design for a cook stove, the design for the end plate of the water reservoir, substantially as described and shown.

8. In a design for a cook stove, the design

for the back plate, substantially as described and shown.

9. In a design for a cook stove, the design for the smoke flue, substantially as described and shown.

10. In a design for a cook stove, the design for the end plate of the warming oven, substantially as described and shown.

11. In a design for a cook stove, the design

for the front doors of the warming oven, substantially as described and shown.

In testimony whereof I have signed my name to this specification in the presence of two subscribing witnesses.

JOSEPH LEON GOBEILLE.
